EDWARD VOLTERS

BY

Richard D. Owen
ATTORNEY.

UNITED STATES PATENT OFFICE.

EDWARD VOLTERS, OF ST. LOUIS, MISSOURI.

COLLAPSIBLE BATHTUB.

Application filed July 5, 1921. Serial No. 482,308.

To all whom it may concern:

Be it known, that I, EDWARD VOLTERS, a citizen of the United States, residing at St. Louis, in the county of St. Louis City and 5 State of Missouri, have invented certain new and useful Improvements in Collapsible Bath-tubs, of which the following is a specification.

This invention relates to new and useful 10 improvements in collapsible bath-tubs and more particularly to the type illustrated in my former United States Patent Number 1,307,942, the primary object of the invention being to generally improve the same 15 to add to the efficiency thereof.

More particularly, the present invention aims to improve the corner members of the collapsible frame to prevent bulging of the flexible container supported within the 20 frame, at the same time not interfering with the foldable feature of the frame.

Another object of the invention is to provide simple and easily operated means for locking the frame in an open position.

25 A still further object of the invention is to provide the flexible container with hooks which may be quickly and easily engaged with and disengaged from the collapsible frame, other means being carried by the 30 folded portions of the container for preventing these portions from sagging.

Other objects and advantages of the invention will become apparent during the course of the following description.

35 In the accompanying drawings forming a part of the application and wherein like numerals are employed to designate like parts throughout the several views,

Figure 1 is a perspective view of the tub 40 set up,

Figure 2 is an elevation of the frame partly collapsed,

Figure 3 is a perspective view of the locking feature embodied in the frame,

45 Figure 4 is a sectional view illustrating the improved means for supporting the container within the frame,

Figure 5 is a perspective view of the same,

Figure 6 is a perspective view of a lower 50 corner of the frame,

Figure 7 is a vertical section through the same,

Figure 8 is a rear elevation of one end of my improved corner members,

55 Figure 9 is a perspective view of my improved lower corner member, and

Figure 10 is a perspective detail of the upper end of an improved corner member and fasteners carried by the container adapted for association therewith.

60

Referring now more particularly to the drawings wherein for the purpose of illustration are shown the preferred embodiments of my invention, the collapsible frame is essentially of the same construction as that shown in my former Patent 1,307,942, and consists of sectional side bars 11 and end bars 12 pivotally connected at their ends with upper corner members 13. As best seen in Figure 3, the sections of each sectional bar are pivotally connected together as at 14, it being noted that the end of one section is extended beyond the pivotal connection and is provided upon its lower edge with a lateral extension 15 forming a support for the coacting section of the bar when the frame is set up. The sections of the bars 11 and 12 are adapted to swing upwardly in order to collapse the frame and to prevent this movement when the frame is set up, the sections coacting with the lateral extension 15 are provided each with a pivoted latch having its free end notched for straddling the lateral extension 15. As the lower edges of the sections carrying the latches rest upon the lateral extensions 15, it will be seen that the sectional bars can neither swing upwardly or downwardly while the latches 16 are engaged with these extensions.

90

As in my above mentioned patent, a set of lower corner members 17 are provided for the frame. As best seen in Figure 9, the angle of each L-shaped corner piece is bridged by a strip 18 having its ends angularly disposed to be fastened to the free ends of the arms of the corner members thereby forming a socket 19 in each corner member 17.

95

Collapsible structures 20 and 21 form the side and ends respectively of the frame, the structure 20 each assuming the form of a lazy tongs, opposite ends of which are pivotally connected to its respective upper and lower corner members 13 and 17 respectively. The collapsible structures 21 forming the ends 100 of the frame each consist of a pair of bars pivoted together between their ends, while their free ends are pivotally connected to the upper and lower corner members.

105

As best seen in Figures 6, 7, 8 and 9, an L-shaped member 22 is riveted within the lower end of each corner member 13 and

each member 22 is provided with a depending extension 23 formed to snugly fit within the socket 19 of its respective lower corner member 17.

- 5 As clearly shown in Figure 10, a strap 24 having angularly disposed ends is riveted to the inner faces of the arms of each corner member 13 at the upper end thereof and forms a socket as clearly seen for a purpose
10 which will presently appear. The flexible container indicated in its entity by the numeral 25 is in the present instance rectangular in configuration and the upper edges thereof are provided on the exterior thereof
15 with downwardly pointing hooks 26 which are adapted to overlap and embrace the sectional bars 11 and 12 of the frame for supporting the container therein. The hooks 26 each form an integral part of a fastening
20 plate 27 extending laterally beyond opposite sides thereof. As clearly seen in Figure 5, the upper edges of the flexible container are folded upon themselves and are clamped between the plates 27 carrying the hooks and
25 corresponding plates 28, rivets passing through these plates and containers for connecting them. The folded portions of the ends of the container are provided with double hooks 29 fastened to the container
30 in a manner similar to the plates 27. As clearly seen in Figure 10, these double hooks 29 are adapted to overlap the shoulders of the plate 27 upon opposite sides of the hooks 26. The latter are adapted to fit into the
35 sockets formed in the upper ends of the corner members 13, and it will therefore be obvious that the sides and ends of the flexible container will be effectively supported in upright position within the collapsible frame.
40 The metal parts of the invention are preferably constructed from aluminum in order to render the device as light as possible whereby it may be conveniently transported. As the double hooks 29 are provided for the
45 folded portions of the container, it will be obvious that they will maintain these portions in close proximity to the sectional bars of the frame and thereby prevent the admission of water into the pockets formed by the
50 folded portions. As the corner members of the upper set in my above named patent did not extend the full height of the flexible container, the latter would bulge at the corners when water was placed therein, and conse-
55 quently I have found that by making the corner members 13 the full height of the container, this bulging is overcome and inasmuch as the members are detachably associated with the lower set of corner members
60 17, the frame can still be collapsed with equal facility.

The foregoing description and accompanying drawings have reference to what might be considered to be the approved or
65 preferred form of my invention, I desire it

to be understood that I may make such changes in the construction, combination and arrangement of parts material, dimensions, etc., as may prove expedient and fall within the scope of the appended claims.

Having thus described my invention what I claim as new and desire to secure by Letters Patent is:

1. A collapsible bath tub comprising a collapsible frame composed of two sets of corner members for the upper and lower corners of the tub, collapsible structures forming the sides and ends of the frame and connected to said corner members, the upper corner members being elongated to extend 75 the full height of the tub, and the lower ends of said upper corner members being detachably associated with the lower corner members.

2. A collapsible bath tub comprising a collapsible frame composed of two sets of L-shaped corner members for the upper and lower corners of the tub, the lower corner members having sockets therein, collapsible structures forming the sides and ends of the frame and connected to said corner members, the upper corner members being elongated to extend the full height of the tub, and the lower ends of said upper corner members having extensions to be detachably associated with the socket of the lower corner members. 90

3. A collapsible frame including sectional bars, one section of each bar having a laterally extending lug for the support of the co-acting section of the bar, and a notched latch carried by said co-acting section and adapted to straddle said lug for locking the sections together. 100

4. The combination with a collapsible frame including L-shaped corner members, a strap for each L-shaped member bridging the angle thereof and forming a socket; of a flexible container having hooks engageable in said sockets. 105

5. The combination with a flexible container; of a folding frame to receive the container, the sides and ends of the frame consisting of lazy tong structures, and corner members extending the full height of 115 the container for receiving the corners thereof and for connecting the sides and the ends of the folding frame.

6. The combination with a collapsible frame; of a flexible container having fasteners engageable with the frame for supporting the sides of the container, and retainer elements carried by certain folded portions of said container and adapted to co-operate with the fasteners for retaining the folded 120 portions of the container in proximity to the walls thereof and for preventing the folded portions from slipping longitudinally along the ends of the frame in either direction. 125

7. The combination with a collapsible frame; of a flexible container adapted to be opened to fit within said frame, fasteners carried by the container for engagement 5 with the frame, and a retaining element comprising a pair of spaced hooks carried by a folded portion of the flexible container and adapted for engagement with a fastener for retaining the folded portion of the container 10 in proximity to a wall thereof.
8. The combination with a frame; of a flexible container adapted to be opened to fit within said frame, laterally extending hooks carried by the container and having
- depending ends for engagement with the 15 frame, and a retainer element carried by a folded portion of the container and including a pair of spaced laterally projecting hooks having depending ends, said pair of hooks being adapted to be arranged on opposite 20 sides of one of the first mentioned hooks.
- In testimony whereof I affix my signature in presence of two witnesses.

EDWARD VOLTERS.
